MEANS FOR FABRICATING PIEZOELECTRIC CRYSTAL UNITS

Filed Oct. 16, 1942

FIG.1

FIG.2

INVENTOR.
ALFRED L. W. WILLIAMS

BY

DR Goldsborough

UNITED STATES PATENT OFFICE

2,414,574

MEANS FOR FABRICATING PIEZOELECTRIC CRYSTAL UNITS

Alfred L. W. Williams, Cleveland Heights, Ohio,
assignor to The Brush Development Company,
Cleveland, Ohio, a corporation of Ohio

Application October 16, 1942, Serial No. 462,236

3 Claims. (Cl. 90—20)

1

This invention relates to means for fabricating piezoelectric crystal units.

As pointed out in the United States patent to Sawyer et al., No. 2,112,636, the fabrication of extremely thin piezoelectric crystal sections from Rochelle salt or the like, is best accomplished in four steps, i. e., producing a relatively thick slab of crystalline material from mother crystal, sawing the slab into a plurality of plates, subjecting the plates to a milling operation and thereafter to a turning operation whereby the sections are reduced to the exact thickness desired.

Should extreme thinness not be a requirement, the last step may be omitted, provided that the milling operation is such that it produces dimensionally accurate sections having parallel, smooth surfaces to which electrodes may be caused to adhere. The first and second steps of the process may satisfactorily be accomplished through utilization of the apparatus disclosed in the United States patent to Sawyer, No. 1,764,088. Because of the extreme frangibility and sensitivity to heat of Rochelle salt sections, however, the employment of conventional milling cutters, intended for use on metals, results in excessive spoilage and consequent waste.

The primary object of this invention, therefore, is to produce apparatus for subjecting a section of frangible piezoelectric material to a milling operation without causing breakage or causing spoilage because of heat.

Another object is to produce apparatus of the type described through the employment of which dimensionally accurate piezoelectric crystal sections having smooth, parallel faces may be fabricated.

The foregoing objects and other objects ancillary thereto are accomplished, in a preferred embodiment of the invention, by causing a crystal section to so move horizontally in a plane parallel to and slightly below the axis about which a horizontally extending milling cutter rotates that the cutter makes line contact with the upper face of the crystal and removes therefrom a surface layer having predetermined thickness. A roughing and a finishing cutter may be disposed, sequentially, adjacent to the path of movement of the crystal section, if desired.

For the purpose of preventing heat from spoiling the crystal section, it is supported upon a massive table of material having high heat conductivity, such as metal, which table may be caused to reciprocate in a horizontal plane or

2

to rotate about a vertical axis to bring the section in contact with the cutter or cutters.

Inasmuch as it is inexpedient to employ mechanical devices for holding the section to the moving table while the said section is being subjected to the milling operation, means are provided whereby atmospheric pressure is utilized automatically, so to speak, for that purpose. In order that atmospheric pressure shall be applied to the crystal section during the time that it is being milled, the table is provided with a plurality of small channels that extend between the upper and lower faces thereof and means, such as a vacuum pump, are provided for exhausting air from the channels immediately below the section and closely adjacent thereto only while the section is in the neighborhood of a cutter. The movement of the table into and out of the work zone controls the application of the vacuum, in the preferred embodiment, thus facilitating the loading of the table with sections and their removal therefrom subsequent to the milling operation.

The novel features considered characteristic of the invention are set forth with particularity in the appended claims. The invention itself, however, both as to its organization and its method of operation, together with additional objects and advantages thereof, will best be understood from the following description of a specific embodiment, when read in connection with the accompanying drawing, wherein:

Figure 1 is a plan view, partly broken away, showing the essential elements of a milling cutter constructed according to the invention, and

Figure 2 is a view, partly in elevation and partly in vertical cross section along a line substantially corresponding to the line II—II in Figure 1.

In both figures of the drawing, identical elements are similarly designated. It is to be understood, also, that many conventional portions of the apparatus, such as the prime mover, the vacuum pump, the means for adjusting the position of the cutter vertically with respect to the crystal sections, etc., have been omitted inasmuch as they form no part of the present invention.

Referring now to the drawing, the preferred embodiment of the invention includes a circular work-supporting table 1, keyed to a vertical spindle 3 which receives relatively slow rotary motion from a prime mover (not shown). Suitable bearings of conventional type (not shown) are provided for the spindle and the table, if

desired, may be supported at its periphery upon a fixed circular track of conventional type, also not illustrated because it forms no part of the present invention. The table is provided with a large number of small channels 5, that terminate in openings in the upper and lower faces thereof. A rotary milling cutter 7 is mounted to extend inwardly over the upper face of the table from the periphery in the direction of the spindle, the axis of rotation of the cutter being parallel to the plane of rotation of the upper surface of the table. Means (not shown) are provided for raising and lowering the cutter and for holding it spaced a definite measurable distance above the table to determine the depth of cut taken from a crystal section 8 as it is carried beneath the cutter by the rotating table.

To provide means for guiding and urging a crystal section beneath the cutter, the upper surface of the table carries a masking disc 9 having a plurality of angularly spaced crystal-receiving windows 11 formed therein.

A threaded extension 13 of the rotary spindle extends through a central aperture in the masking disc and a nut 15, having a wide laterally extending flange 17, is threaded on the spindle and so holds the disc rigidly, yet removably, in fixed position that it revolves with the table.

The windows 11 in the masking disc expose only the openings of the channels extending through the table directly beneath them; the remaining channels are blocked off by the imperforate portions of the disc.

Dimensionally, the windows are slightly longer and somewhat wider than the particular crystal section which is to be subjected to the milling operation, thus facilitating loading and unloading. Should it be desired to operate upon crystal sections that previously have been provided with electrodes and an electrode lead 18, each window may be provided with a lateral extension 19 to accommodate the lead and to keep it out of the path of the cutter.

The disc, preferably, is fabricated from a material such as a laminated thermo-setting plastic that is fairly hard yet is reasonably flexible; its thickness is somewhat less than that to which the crystal section is to be finally milled.

A wide variety of masks may be provided for accommodating crystal sections of various shapes and thicknesses, thus rendering the cutter extremely versatile. Also, it is to be understood that the entire table may be provided with air channels to further extend the range of usefulness of the apparatus to include crystal sections wider than those shown in the drawing.

In order that atmospheric pressure may be utilized, automatically, for holding a crystal section in place upon the table during the milling operation, the open end of an intake pipe 21 leading to an exhaust pump (not shown) is positioned fixedly beneath the table directly below the milling cutter and the gap between the lower surface of the moving table and the edge of the open end is made air-tight through utilization of packing means such as a resilient gasket 23 disposed around the pipe. Alternatively, the end of the intake pipe may connect with an exhaust chamber (not shown) that offers either a smaller or a larger effective opening to the table than the pipe, depending upon the dimensions of the crystal sections that the apparatus is intended to mill.

When setting the device into operation, the first step is to place a masking disc, having windows of the proper dimensions, upon the table and

to lock it firmly in position thereon by turning down the lock nut. Thereafter, the milling cutter, which rotates in a direction to oppose the movement of a crystal section past it, is set into motion, the exhaust pump or fan (not shown) is started, and the table is caused to slowly rotate in the direction of the arrow in Figure 1. A crystal section is placed in one of the windows as the table moves past station A and the milling cutter is lowered and locked in position to remove a layer of the requisite thickness from the upper surface of the section.

As the table moves toward the "work" position beneath the cutting tool the channels through the table below the section are exposed to the intake of the vacuum pump and atmospheric pressure acts upon the surface of the section to hold it firmly in place until the cutting operation is completed. As the crystal section moves beyond the "work" position, leaving the cutter, the openings of the table channels below the section clear the intake opening and the pressure is released, automatically, thus permitting the operator to remove the finished section and to deposit another one in the window.

No specific directions can be given with respect to the depth of material that may safely be removed from a section during a single "pass" nor can the angular velocity of the table or the revolutions per minute of the cutter be exactly determined in advance. Those factors, obviously, depend upon the size and thickness of the section being milled and upon the efficacy of the metal table in removing heat generated during the milling operation.

To some extent, at least, the table and crystal section are cooled by air that leaks past the crystal and the mask and a separate air-blast for cooling purposes has not been found necessary. An additional exhaust system (not shown) may be provided for carrying away and for recovering the crystalline material removed by the cutter and an air-blast or suction means (not shown) may also be utilized for cleaning the crystal and the table during the cutting operation.

The invention also includes the positioning of more than one milling cutter in the path of movement of the crystal sections, for the purpose of removing the surface of a section in a succession of operations. In that modification, the vacuum may or may not be broken between successive cutters. Obviously, a second cutter could be mounted at a location indicated, for example, by the letter B in Figure 1, and the intake of the vacuum pump, or a chamber connected thereto could extend to cover the table-channels at the second location as well as those included in the arc of movement of a crystal section between the two locations. Such modification of the invention is so obvious that no necessity is seen for illustration thereof.

In the event that it is desired to finish both sides of a section before it is finally removed from the device, a second cutter 7 and exhaust pipe 23 may be added to the apparatus exemplified by Figure 1. The additional cutter, for example, might be mounted diametrically opposite to the cutter shown and another operator, located at a position indicated by the letter C, could remove each section as it leaves the first "work" zone and replace it in the window with the unmilled side uppermost for milling by the second cutter. This additional modification of the invention is believed to be also so obvious as to need no illustration.

The inventor is fully aware of the fact that work-holding means of the vacuum type have been employed hitherto in connection with machine tools and he is familiar with the prior art exemplified, for example, by the United States patent to Pellow et al., No. 1,119,111. Insofar as he is aware, however, the semi-automatic utilization of such vacuum means in connection with the milling of frangible piezoelectric crystal sections is novel with him and it is believed to be an important contribution to the art.

Although several specific embodiments of the invention have been disclosed and described herein, it is to be understood that they are merely illustrative and that other modifications may be made without departing from the spirit and scope of the invention as defined in the appended claims.

What is claimed is:

1. In a machine which includes a work tool, the combination of movable means including a table having a plurality of interior passageways that terminate in openings in a surface thereof for supporting an object and for moving it into engagement with said tool, means for exhausting the air between the object and the supporting means through said interior passageways to establish a holding vacuum therebetween during the time period of engagement of the tool with

5 the object, and masking means removably secured against said table for preventing motion of said masking means with respect to said table and for substantially preventing air from being drawn through passageways adjacent to those covered by the object, said masking means establishing an abutment for helping to hold said object from sliding in a plane parallel to the plane of the face of said table as said work tool operates 10 on said object.

2. The device as defined in claim 1, characterized in this; that said interior passageways terminate in openings extending circumferentially around said table, and said masking means 15 includes a plurality of windows each located adjacent some of said openings and each for receiving one of said objects whereby the openings located under each window exhaust the air between the table and the object positioned in the window.

3. The device as defined in claim 1, further characterized in this; that said interior passageways terminate in openings extending circumferentially around said table whereby a plurality of said openings will always register with the windows in said substitute masks despite the different size or shape of the windows therein.
